UNITED STATES PATENT OFFICE.

ISIDOR KITSEE, OF PHILADELPHIA, PENNSYLVANIA.

PROJECTING MOVING PICTURES.

1,180,655.

Specification of Letters Patent. Patented Apr. 25, 1916.

Application filed March 5, 1914. Serial No. 322,742.

To all whom it may concern:

Be it known that I, ISIDOR KITSEE, a citizen of the United States, residing at Philadelphia, in the county of Philadelphia and State of Pennsylvania, have invented certain new and useful Improvements in Projecting Moving Pictures, of which the following is a specification.

My invention relates to an improvement in projecting moving pictures. Its object is to make the change of picture on the screen without necessitating the employment of a shutter at the projecting machine and yet not permitting the audience to observe this change on the screen.

To-day, the shutter is employed for cutting off the light from the picture screen while the film is in motion during the shift or change of one picture to the succeeding picture and the light from the projecting machine is only allowed to fall on the screen during the time that the picture remains still. It is unnecessary for me to point out the many great disadvantages inherent with this method of projecting pictures, as persons versed in the art well know that the so-called "light rain" or "flicker" is mostly due to the operation of the shutter. Besides, the change from darkness to light on the screen always leaves its ill effect on the eye.

To illustrate some forms my invention may take, I have reference to the accompanying drawings:

In these drawings: Figure 1 is a side elevation of a projecting machine with the screen shown in section and provided with my invention. Fig. 2 is an end view of a rotating commutator; Fig. 3 is a side elevation of a projecting machine with the screen shown in section and provided with my invention in different form.

The projecting machine in these figures is only shown elementary, as my invention does not contemplate a change of the light house, the film, or the means of moving the film, or winding and unwinding the same and is applicable to the different types of machines now in use. The only change on the projecting machine which is required for the purpose of my invention is in replacing the shutter with a commutating device and this commutating device may be placed on the same shaft as to-day the shutter is placed.

In the drawings: 1 indicates the projecting machine, as an entirety, and 2 the screen

as an entirety. Of the projecting machine 1, 3 is the housing for the light; 4 the opening through which the light is thrown on the screen 2; 5 is a shaft on which normally 60 the shutter is placed. On this shaft, to replace the shutter, is the commutating device indicated as an entirety by the numeral 6. This commutating device comprises here the conducting part 7 and the insulating 65 parts 8, 9 and 10, respectively.

11 is a contacting brush. 12 and 13 are the two wires of an electric circuit. The brush is here connected to the wire 12 and part of the wire 13 is connected with such 70 part of the projecting machine as is in electrical contact with the conducting part 7 of the commutating device. The electric circuit is connected to a source of current. 14, 14, are sources of electric light, here 75 shown as incandescent lamps.

The arrangement of the different parts of Fig. 1 may be a duplicate of the arrangement of Fig. 3 with this exception that the sources of electric lights are shown in Fig. 80 1 as to be placed before the screen 2, whereas in Fig. 3, these sources of electric lights are placed in the rear or back of the screen. I have shown in these drawings a three-part commutator, but it is obvious that the 85 commutator may consist of as many segments as are required.

The operation of this, my invention, is as follows:—Instead of having the screen, as usual, normally darkened, I normally illuminate the screen either as is illustrated in Fig. 1 by placing a series of lamps,—incandescent or otherwise,—around the edges of the screen and in front of same, or, as illustrated in Fig. 3, in placing the lamps,—95 incandescent or otherwise—in the rear or back of said screen in such numbers as are required to illuminate the front of the screen for the purposes later on to be described. When, in the operation of the projecting 100 machine, a film carrying images is inserted and then moved so as to bring the image in proper position before the lenses, the spectator would ordinarily see the moving of the image depicted on the screen; but as the 105 screen itself is illuminated to a degree as strong or stronger than the illumination emanating from the projecting machine, it is obvious that as long as this first illumination persists, the shadow of the image 110 thrown on the screen will not be perceived by the eye of the spectator, because

this shadow is eliminated by the illumination of the incandescent lamps at or near the screen. When, now, the image is in its proper position and the electric lights, here 5 designated as 14 and illuminating the screen, are extinguished, then the screen will only be illuminated from the rays of light issuing from the projecting machine and the image on the film will, therefore, be clearly 10 shown on the screen. In the operation of the projecting machine all that is necessary, therefore, is to illuminate the screen with a source of light independent of the source of light of the projecting machine during the 15 time that a change of picture is made in the projecting machine and to cease said illumination when the image on the film is in its proper position and to produce this result, it is only necessary to so adjust the 20 commutating device that during each revolution of the shaft (operatively related to the moving of the film), the brush connects with the conducting part of the commutator during the time of making a shift from one 25 image to the second image and that the brush should connect with the insulating part of this commutator during the time that this image should be exposed to view. In the operation of the machine, we, therefore, have two sources of light impinging 30 on the screen during the moving of the picture film:—one source placed at or near the screen, the second source coming from the projecting machine; and we have only one 35 source of light, that is, the source coming from the projecting machine during the time that the picture film is stationary. Persons versed in the art well understand that as long as the circuit from the source 40 of current is made, the lamps 14 will light, but as soon as the circuit is broken, the lighting will cease.

I have so far described and illustrated the sources of extra illumination placed at 45 or near the screen or curtain. But in some cases, the owner of the house may prefer that the source of extra illumination should be placed in the same inclosure that the moving picture machine is placed. In this 50 case, a separate arc may be positioned near the projecting arc, or the light from the projecting arc may be provided with a second passage, so as to be enabled to impinge the light rays from this arc on the screen without 55 the interposition of the film. But in both cases, lenses or condensers have to be provided, so that the whole surface of the screen should be illuminated.

Having now described my invention, what 60 I claim as new and desire to secure by Letters Patent is:—

1. The method of projecting moving pictures which consists in neutralizing the rays of light from the light-house of the moving 65 picture machine during the time that the

film is in motion through rays of light from sources stationed at or near the screen and destroying said neutralization when the film is at rest.

2. The method of projecting moving pictures which consists in projecting through the picture film rays of light on the screen during the moving of said film as well as during the time said film is stationary, and neutralizing the result of said rays of light 75 with the aid of rays of light emanating from sources of light stationed at or near the screen, during the time that said film is stationary.

3. In the art of exhibiting moving pictures the method which consists in normally illuminating the screen with the rays from two sources of light, one of said sources stationed at or near the screen and one of said sources stationed at or near the moving 85 picture machine and automatically cutting off the rays from the source of light stationed at or near the screen during the time that the picture film is at rest.

4. In a device of the class described, two 90 sources of light, normally illuminating the screen on which the pictures are to be projected, one source stationed at or near the picture film, the second source stationed at or near the screen and means, automatic in 95 their action, to cut off the source of light stationed at or near the screen, at predetermined periods, said means operatively related to the movement of one of the shafts of the projecting machine. 100

5. In a device of the class described a screen adapted to have projected thereon pictures, two sources of light illuminating said screen, one source of light stationed at or near the picture film, the second source 105 of light stationed at or near the screen and automatic means to cut off the source of light stationed at or near the screen during the time that said picture film is at rest. 110

6. In the operation of moving picture devices the improvement which consists in transmitting rays of light through the picture film uninterruptively during the whole time of operation, from the source of light 115 stationed at or near said film and eliminating the shadows due to the opaque places in said picture film through sources of light, illuminating the screen and stationed at or near said screen, and adapted to be cut off at predetermined periods. 120

7. In a device of the class described a picture film, means to move the same, a screen adapted to have the pictures projected thereon, a source of light stationed at or near said film, a second source of light stationed at or near said screen and means, automatic in their action, to cut off the source of light stationed at the screen at predetermined periods, said means opera- 130

tively related to the movable parts of the means to move the film.

8. In the art of exhibiting moving pictures, the improvement which consists in illuminating the screen adapted to have the pictures projected thereon, during the time that the picture film is moving with two sources of light, one source of light stationed at or near the picture film, one source of light stationed at or near the screen and causing the source of light, stationed at or near the screen, to be cut off during the time that said film is stationary.

9. In the art of exhibiting moving pic-

tures the improvement which consists in projecting said pictures on a screen during the time that the film is moving as well as stationary and destroying or neutralizing the shadowy effect of said pictures on said screen during the time that said film is moving, through a source of illumination stationed at or near the screen.

In testimony whereof I affix my signature in presence of two witnesses.
